COMMERCIAL PACKAGE

Walter F. Straub, Chicago, Ill., and Edwin W. Fuerst, Toledo, Ohio, assignors, by direct and mesne assignments, to W. F. Straub & Company, Chicago, Ill., a corporation of Illinois

Application December 17, 1932, Serial No. 647,704

7 Claims. (Cl. 206—44)

The invention relates to a commercial package for dispensing honey or honey products.

A general object of the invention is to provide a novel commercial package for honey which is neat and attractive in appearance and which embodies an arrangement of parts presenting or including a pattern having the characteristics of a honeycomb whereby the nature of the contents of the package is clearly portrayed.

10. Another object resides in the provision of a container for honey or the like wherein a substantially flat surface on the container presents a pattern which in size and configuration is characteristic of a honeycomb, the container being of a substantially transparent material so that the color of the contents is superimposed upon the pattern.

20. A further object is to provide a container of the character above set forth in which the filling and emptying opening is, in the commercial package, concealed within an enclosing element (which is capable of being advantageously utilized for advertising matter), said element being so arranged that it coats with the container to set apart the surface on which the honeycomb pattern is disposed, and having elongated parts or strips extending about the container and similar in shape to the frame in which a natural honeycomb is usually contained.

25. Other objects and advantages will become apparent in the following description and from the accompanying drawing in which Figs. 1 and 2 are front and side views respectively of a commercial package embodying the features of the invention.

30. Fig. 3 is a horizontal section taken through one corner of the container.

Fig. 4 is a vertical central section through the package with part of the container shown in elevation.

Fig. 5 is a perspective view of the enclosing element for the container.

Fig. 6 is a vertical section taken substantially along the line 6—6 of Fig. 1.

45. The structure of the container per se is covered by my copending application, Serial No. 42,070, filed September 25, 1935.

The present invention contemplates generally a pleasing and attractive commercial package for merchandising honey or the various products thereof. The package is characterized by a resemblance to the conventional comb honey article, which resemblance is attained preferably by providing on a container a pattern conform-

ing substantially in size, shape and arrangement to the comb, and by forming the container of a material which is transparent, or substantially so, whereby the color of the honey through the pattern on the container indicates to a customer the nature of the contents of the package.

The preferred container has, of course, a filling and receiving opening which in the present commercial package might possibly detract from the desired representation. The container is therefore adapted to fit, in part, into a box-like structure which conceals the said opening and the container parts closely adjacent thereto and exposes the parts of the container upon which the pattern is depicted. This structure may be utilized to present printed or advertising matter to the customer.

The box-like structure preferably includes elongated members which extend about the container for the purpose of securing the structure thereto as well as to further emphasize the impression of a comb-honey package.

A package thus constructed and fashioned not only gives the impression of neatness and cleanliness, but has the important advantage of attracting and holding the customer's attention whereby to facilitate and increase sales. Moreover, the package is quite inexpensive to produce and assemble.

Referring more particularly to the drawing, in which a preferred embodiment of the invention is shown for illustrative purposes, 10 designates a container, fashioned in this instance, of substantially clear glass and generally in the form of a bottle of rectangular cross-section. Herein, the container presents flat front and rear faces 11 of substantial area, and considerably narrower flat side faces 12. The upper or shoulder portion of the container is restricted in the usual manner, as at 13 (Fig. 4), to provide a neck 14 defining a filling and emptying opening which is closed by any well known type of detachable closure 15.

Separating the upper or shoulder portion and the lower or body portion of the container is a transverse rib 16 which preferably extends entirely about the container to provide an upwardly facing ledge 17 (Figs. 4 and 6). The rib 16 is so located as to set-off on the two larger faces 11 of the body portion a substantially square area. Preferably the rib 16 and the side and bottom corners 18 (Fig. 1) of the container are rounded to emphasize the square area bordered thereby.

One or both of the square areas carry a pattern having the characteristics of a honeycomb. That is to say the pattern is comprised of a series

of lines, ribs or the like defining a plurality of abutting hexagonal figures. In this embodiment the pattern is defined by ribs 19 formed in the process of moulding the container. If desired the honeycomb characteristics of the pattern may be enhanced by lightly stippling or roughening the majority of the hexagonal figures thus formed to produce a cloudy or hazy effect.

The filling and emptying apertures, the closure therefor, and the associated parts of the container above the ledge 17 are preferably concealed by a rectangularly shaped box-like structure 20 adapted to fit over the upper portion of the container with the margins of the structure snugly engaging against the ledge 17. The structure is so dimensioned that it forms a continuation of the sides of the container body when assembled thereon. The ledges 17 across the narrow faces 12 are substantially as deep as the thickness of the material from which the structure is fashioned so that when the package is viewed in front elevation, there are no appreciable bulges on the sides. The structure may be economically fashioned of heavy paper, cardboard or like materials and presents five plane sides, any or all of which may be effectively used for printed matter such as trademarks, ornamental designs, directions, or advertising matter.

Extending from the opposite end walls of the structure are elongated strips 21 which pass downwardly over the ribs 16, along the narrow side faces 12, and thence beneath the bottom of the container where the strips meet for connection together. Such connection is by any well known means such as adhesive, metal clips or, as shown at 22, by interlocking slots and tabs fashioned in the strips. Since the ribs 16 and ledges 17 across the sides 12 are not deep, the strips may pass over the ribs without being noticeably offset.

As is best shown in Figs. 2 and 5, the opposite sides of the strips 21 have elongated recesses 23 formed along those portions of the strips which are disposed adjacent to the square area portion of the body and the strips below the rib 16 may be tinted and grained to resemble wood. Thus the strips conform in shape and color to that of the wooden frame customarily employed to support a honeycomb. The corners of the container which in assembly are adjacent the recessed parts 23 of the strips may have elongated vertical indentations or grooves 24 (Figs. 1, 2 and 3) therein to further impart a natural appearance to the package.

It will be evident from the foregoing that a novel commercial package for honey has been produced which will effectively arrest the attention of possible purchasers. The natural honey color as seen through the container walls and superimposed on the honeycomb pattern produces a pleasing effect which immediately indicates the nature of the contents, and the effect thereof is amplified by the formation and character of the side strips 21 and the corner grooves 24.

While the invention is susceptible of various modifications and alternative constructions, we have shown in the drawings and have herein described in detail the preferred embodiment, but it is to be understood that we do not thereby intend to limit the invention to the specific form disclosed, but intend to cover all modifications and alternative constructions falling within the spirit and scope of the invention as expressed in the appended claims.

We claim as our invention:

1. A commercial package for honey comprising, in combination, a container of rectangular cross section formed of a substantially transparent material and having a top filling and emptying opening therein, a shoulder extending about said container below said opening and arranged to set off substantially square surfaces on the larger faces of said container, ribs traversing at least one of said square surfaces and arranged in a pattern characteristic of a honeycomb, and an advertising carrying element adapted to conceal said opening comprising a box-like structure having an open face into which the upper end of the container fits with the margins of the structure 18 engaging said shoulder, and side members extending from said box-like structure downwardly along the opposite sides and thence beneath the bottom of said container for connection together to secure the structure on the container, said side members being marginally recessed in the portion thereof adjacent to the square surfaces, and the container having vertical grooves along the sides thereof adjacent to said square surfaces.

2. A commercial package for honey comprising, in combination, a container formed of a substantially transparent material and having a top filling and emptying opening therein, a shoulder extending about said container below said opening and arranged to set off substantially square surfaces on the larger faces of said container, means on at least one of said square surfaces presenting a pattern characteristic of a honeycomb, and an advertising carrying element adapted to conceal said opening comprising a box-like structure into which the container fits with the structure resting against said shoulder, and side members extending from said box-like structure downwardly along the opposite sides and thence beneath the bottom of said container for connection together to secure the structure on the container.

3. A commercial package comprising, in combination, a container having a transverse ledge thereon, a box-like structure adapted to receive a part of said container and dimensioned to abut against said ledge and provide a continuation of the exposed part of said container with the exposed surfaces of the container and structure substantially flush, and strips extending from the structure along opposite sides of the container and thence toward each other along another side for connection together to secure said structure and container together, said ledge underneath said strips being shallow to prevent substantial offsetting of said strips at those points.

4. A commercial package comprising, in combination, a container having a body portion and a shoulder portion provided with a filling and emptying opening, a box fitting over the shoulder portion, and strips extending from said box along opposite sides of said body portion and thence toward each other across a third side for connection together, at least one of the exposed faces of said body portion having thereon a pattern characteristic of a honeycomb, said strips being fashioned in resemblance of a frame in support of a honeycomb.

5. A commercial package for honey comprising, in combination, a container formed of a substantially transparent material and having a top filling and emptying opening therein, a shoulder extending about said container below said opening and arranged to set off substantially square surfaces on the larger faces of said container, and

- an advertising carrying element adapted to conceal said opening comprising a box-like structure into which the container fits with the structure resting against said shoulder, and side members 5 extending from said box-like structure downwardly along the opposite sides and thence beneath the bottom of said container for connection together to secure the structure on the container.
6. A commercial package comprising, in combination, a container having at least one face 10 fashioned to resemble a honeycomb and having portions surrounding said face fashioned to resemble the frame of a honeycomb, said container also having a top portion extending above said face 15 and provided with a filling and emptying opening, and a structure comprising a box-like portion fitting over and hiding from view said top portion of the container, and retaining means extending

downwardly around the sides of the container for holding the box-like portion in place.

7. A commercial package comprising, in combination, a container comprising a body portion and a neck portion provided with a filling and emptying opening, and a box-like cardboard structure wholly enclosing the neck portion and telescoping over and fitting snugly about the adjacent part of the body portion, said box-like structure having straps of cardboard integrally attached thereto and extending around the sides of the container to maintain said structure in position, said structure being adapted to provide space for advertising matter and to be removed from the container and discarded when the contents 15 of the container are to be used.
